UNITED STATES PATENT OFFICE.

RAYMOND KELLY AND GERTRUDE E. LONG, OF CHICAGO, ILLINOIS, ASSIGNEES OF ONE-THIRD TO GIBSON AND GIBSON, OF CHICAGO, ILLINOIS, A COPARTNERSHIP COMPOSED OF JAMES D. GIBSON AND RAYMOND GIBSON.

DESIGN FOR A DOLL.

Application filed January 20, 1923. Serial No. 4,952. Term of patent 3½ years.

To all whom it may concern:

Be it known that we, RAYMOND KELLY and GERTRUDE E. LONG, citizens of the United States, residing at Chicago, in the county of Cook and State of Illinois, have invented a new, original, and ornamental Design for Dolls, of which the following is a specification, reference being had to the accompanying drawing, forming part thereof.

On the drawing, the single figure is a front elevation of a doll embodying our design.

We claim.

The ornamental design for a doll, as shown.

RAYMOND KELLY.
GERTRUDE E. LONG.
